COMB

Crofton C. Holden, Leominster, Mass., assignor
to Tilton & Cook Co., Leominster, Mass., a cor-
poration of Massachusetts

Application March 15, 1939, Serial No. 262,062

2 Claims. (Cl. 132—21)

The present invention relates to combs for the hair, and is particularly concerned with what are normally referred to as side or back combs which are intended to remain in place closely 5 hugging the head wherever inserted in the hair.

The purpose and object of the invention is to provide a comb which may be conveniently inserted in the hair and thereafter remains snugly in place until removed.

With this object in view, the invention contemplates the production of a curved comb to fit the head, having a series of uniformly disposed teeth which are so shaped and positioned with relation to one another that they provide gradually

narrowing throat portions for the entrance of the hair as the roots of the teeth are approached, terminating in a narrow orifice which abruptly emerges into an enlarged opening within which the lock or strand of hair is trapped to retain 10 the comb against accidental withdrawal in a direction opposite to that of its insertion.

In the accompanying drawing illustrating the preferred form of the invention, Fig. 1 represents an elevation of such a comb; Fig. 2 is a perspective; and Fig. 3 is a section on the line 3—3 of Fig. 1.

The comb shown in the illustrated embodiment of the invention may be conveniently made of thermo-plastic or other suitable material, and is provided with a back portion 19 from which project a series of uniformly disposed teeth 12 which are comparatively long with respect to the dimensions of the comb, the teeth being generally curved as indicated in Figs. 2 and 3 to cause the comb to generally fit the contour of the head. The teeth terminate in reduced and rounded end portions as shown at 14 and are parallel-sided throughout the major portion of their length to provide uniform spaces therebetween ample for the convenient entrance of a strand of hair. As the root or upper portions of the teeth are approached, the sides of the teeth diverge as generally indicated in the area at 16 to provide a gradually narrowing space or throat therebetween terminating in a narrow orifice 18 at the widest portion of the teeth. Beyond this portion the teeth are abruptly cut away at their root junctions and separated by circular openings 20 to cause trapping of the strands of hair therein after the latter have emerged from the narrow orifices into the enlarged circular portions. The trapping is due not only to the narrow openings, but to the rather abrupt shoulder which is formed by the junction of the circular opening and the narrow exit, which tends to prevent withdrawal of the comb in a direction oppo-

site to that of insertion compelling the strands of hair to pass outwardly from the circular openings through the narrow entrance slots.

Inasmuch as the holding or trapping portions of the comb are formed at the upper portions of the teeth, the comb under this arrangement is held snugly in the position in which it is placed, with the length of the teeth completely buried in the hair and with only the back portion exposed. With this construction there is no possibility of a partial loosening of the comb due to its working back to a point where the hair is caught and retained.

What is claimed is:

1. A comb for the hair, comprising a back portion, a series of uniformly spaced teeth terminating in reduced end portions, the teeth being parallel sided throughout the major portion of their length and providing ample space for the passage of a lock or strand of hair therebetween, the individual teeth gradually widening as their roots are approached to gradually and similarly narrow the space therebetween and provide a narrowing throat portion restricted to virtually a narrow slot at the widest portion of the teeth, the teeth beyond the widest portion at the root junctions being abruptly cut back to form hair-retaining shoulders, the teeth being separated in this area by enlarged openings from which the narrow slots at the end of the throat portions emerge to facilitate insertion of the comb into the hair with a lock or strand of hair passing easily from the gradually restricted throat into the openings and trapping the hair therein in a manner to prevent accidental dislodgment and to hold the comb with the length of the teeth firmly buried in the hair.

2. A comb adapted to be worn in the hair comprising a back portion, a plurality of uniformly spaced teeth integral with and extending from said back portion, apertures through said back portion, said apertures being positioned between the bases of adjacent teeth, the lateral sides of the individual teeth being parallel for the major portion of the length of the teeth, the lateral sides of each tooth, however, diverging at an appreciable angle near the root of the tooth to thereby provide restricted spaces between adjacent teeth near their roots, said restricted spaces extending into said apertures, the walls of which cooperate with the diverging sides of said teeth to provide abrupt angular shoulders for preventing unintentional escape of locks or strands of hair entering said apertures through said restricted spaces.
